JOHN W. AREGOOD AND GEORGE H. AREGOOD, OF WASHINGTON, DISTRICT OF COLUMBIA.

BRICK AND TILE CUTTING MACHINE.

SPECIFICATION forming part of Letters Patent No. 466,145, dated December 29, 1891.

Application filed April 27, 1891. Serial No. 390,533. (No model.)

To all whom it may concern:

Be it known that we, JOHN W. AREGOOD and GEORGE H. AREGOOD, of Washington city, in the District of Columbia, have invented a new and useful Improvement in Brick-Machines, of which the following is a specification.

This invention is an improvement in that class of brick-machines wherein the clay is formed into a long slab or slabs fed along a carrier, then cut into brick lengths, and then fed off the carrier; and the present invention seeks to provide improvements in the cutting devices and means for operating the same, a novel construction of carrier and other improvements hereinafter described; and the invention consists in certain features of construction and novel combinations of parts, as will be hereinafter first fully described, and 20 then pointed out in the claims.

In the drawings, Figure 1 is a side view of our machine. Fig. 2 is a top plan view. Fig. 3 is an end view thereof, and Figs. 4 and 5 are detail views.

The apparatus is designed to embody a pug-mill A and machines B, arranged on opposite sides thereof, but as said machines B are alike in construction, it is thought that the illustration and description of one will suffice.

Inasmuch as the devices in the pug-mill for mixing and forcing the clay out in slabs are not claimed to be of our invention a detailed description or illustration thereof is thought to be unnecessary. The shaft C of this mill

35 may be driven by belt D, as shown, or in other suitable manner, as desired. At or near its lower end the shaft C is provided with a master-wheel E, which is formed or provided with cams to give endwise movement to the 40 rod F, which serves to operate the cutting mechanism, and also serves to throw into and out of operation the devices for feeding the cut bricks off the carrier. In the construction shown the cam G is a groove formed in 45 the wheel and entered by a roller or projection H, mounted on the rod F; but manifestly the form and character of the cam may be varied without departing from the broad principles of our invention, the purpose being to 50 reciprocate the rod F by the turning of the master-wheel.

The machine B has a suitable main frame I, a cutter-frame J, a carrier K, a receiving-table L, which is preferably hollow and heated by steam or in other suitable manner, a discharge-belt M, and operating-gearing and clutch mechanism, as will be described.

The main frame I has its legs I' provided with suitable guides i for the upright bars j of the cutter-frame J. On the top frame we 60 support bearings N for the rollers O of the several belts P, which constitute the carrier K. Cross-plates Q are arranged close to the ends of the belts P, and are arranged at their upper sides flush with the upper sides of the 65 belts. It will be noticed that two of these cross-plates are arranged between each two belts and that the cross-plates are separated, forming a groove or way q between them, into which the cutting-wire projects, as herein- 70 after described. While it is preferred to form the adjacent cross-plates Q entirely distinct and to provide the groove q by setting the said plate slightly apart, it is manifest that the adjacent plates may be formed integral 75 at the base or in one piece grooved centrally along the top to form the separated side plates and the recess to receive the cutting-wire. It will be seen that the cross-plates form, practically, a connecting portion be- 80 tween the adjacent belts to support that portion of the clay which lies between two belts, and further to form an unyielding base for the clay on opposite sides of and practically at the point where it is cut off.

The tops of the belts P are about flush with the table L, so that strips of clay forced from the pug-mill over the said table will pass onto the first belt P and thence on across the other belts. The several belts P are driven, in feeding the cut bricks off the machine, by means of a sprocket-chain R meshing sprocket-wheels o on one or both rollers O of each belt P, such sprocket-chain R being driven in the manner presently described. It is preferred 95 to connect the sprocket-wheels o with their shafts O' by clutches S, so that the belts may move forward independently of the sprocket-wheels and chain. Now this is of especial importance, as in forcing the slabs of clay 100 across the carrier the belts may move with it independently of the sprocket-wheels, so that

the said belts will in a measure serve as rollers upon which the slabs move forward, so that instead of the slabs being forced along the belts and become rucked up by friction therewith the belts are moved forward by the slabs of clay and so serve as rollers for the clay as the latter moves forward to position upon the carrier. The particular form of clutch shown includes ratchet-disks 1, fixed 5 on the shafts O', and the ratchet-disks 2, fixed to the sprocket-wheels and normally in contact with the disk 1. The operation of said mechanism will be fully understood from the foregoing description in connection with the 10 drawings.

At the rear end of the machine the carrier delivers the cut bricks to a discharge-belt M, off which they may be taken by hand. This belt is passed around guide-rollers 3, 4, and 5 15 and a drive-drum 6 on a shaft 7. This shaft 7 also has a pinion 8 and a bevel-gear 9. The pinion 8 meshes a gear-wheel 10, which in turn meshes a pinion 11 on one of the rollers O, usually the rear one of such rollers, as 20 shown. The bevel-gear 9 is meshed by a pinion 12 on a shaft 13, to which is fixed a clutch-section 14. A clutch-section 15 is movable into and out of engagement with the clutch-section 14, and is supported on a shaft 16, having 25 fixed and loose pulleys 17 and 18, which may receive a drive-belt from any suitable drive-shaft.

The clutch-section 15 is moved into and out of clutch with the section 14 by means of the 30 crank-arm 19 on the rock-shaft 20, such crank-arm being connected by rods or links 21 with the clutch-section 15, so that the rocking of the shaft 20 moves the clutch-section into and out of engagement with the section 14, in order 35 that the shaft 13 and the parts geared therewith may be driven at certain intervals in the operation of the machine, as will be further explained hereinafter. This shaft 20 and a similar shaft 22 have crank-arms 23, to 40 which the slide-rod F connects, and they are also provided with crank-arms 24, connected by links 25 with the uprights j of the cutter-frame. It will be seen, therefore, that the longitudinal movement of the rod effects the 45 vertical movement of the cutter-frame and also the movement of the parts necessary to adjust the connections between the drive-shaft 16 and the shaft 13, as before described.

The cutter-frame is provided with the cutter-bows 26, which are spring-metal plates secured between their ends to the top bar of the frame J and adapted at their ends to receive the wires 27, which are held taut by the tension of the bows, such tension resulting in 50 the construction shown, from the resiliency of the spring-plates and the supplemental springs 28. The springs 28 are supported on a rod 29, extended between and through the arms of the bow, provided outside said arms 55 with heads or nuts 30 and between their ends with nuts 31, the springs 28 bearing between the nuts 31 and the arms of the bow, so that

the tension of said springs may be regulated by adjusting-nuts 31, as will be readily understood. The spring-bow operates as a spring 70 or yielding support for the cutting-wires 27, which are of considerable importance, inasmuch as it avoids the breaking of the wires. In case they should come in contact with a stone or other unyielding body in the clay the wires 75 will yield and not be broken, as would result if they were stretched in an unyielding support. To enable the convenient application of wires to the bows, we provide compressing devices for forcibly bringing the ends of the 80 bows nearer together. In the construction shown the compressing device includes a lever 32, which fulcrums between one of the heads 30 and the side arm of the bow arranged at its lower end to bear against the said arm 85 and having its upper or handle end provided with a detent-pawl 33, engaging a ratchet 34. When it is desired to apply a wire to the bow, the lever 32 may be pressed out at its upper end. This will force the ends of the bow inward toward each other, in which position they will be held by the ratchet and pawl while the wire is being applied, when the pawl may be released and the bow will expand and hold the wire taut. 95

In practice we make the belts P of clear gum, so that they may be fitted tightly on their rollers and will not be injuriously affected by the moisture in the clay.

It will be understood that in practice we 100 prefer to arrange machines B on opposite sides of the pug-mill and operate the latter to force slabs of clay alternately to the said machines.

The slabs forced from the pug-mill pass 105 across the heated table L onto the carrier, the belts of which are moved by the moving clay and render the forward movement thereof easier, as will be readily understood. When the slab has been forced onto the table, the 110 master-wheel will have been revolved to such extent as to bring its cam to such position as to force the slide-rod forward. This movement of the slide-rod operates through the rock-shafts and their crank-arms and connections to lower the cutting-frame, forcing the wires through the clay and below the same 115 into the grooves q, and then move the clutch-section to cause the gearing to operate to advance the carriers and feed the cut bricks out 120 of the machine.

It will be seen that the cutting-wires do not move upward through the cuts made by them in the clay, and so give the ends of the bricks a ragged appearance; but after forming a 125 clean cut through the slabs the wires remain in the grooves q until the bricks are fed off the machine. After the carrier has been operated to feed the bricks off, the cam of the master-wheel will operate the slide-rod to lift 130 the cutter-frame and adjust the clutch-sections apart, when slabs of clay will again be forced onto the carrier, and the operation proceeds, as before.

Having thus described our invention, what we claim as new is—

1. A machine substantially as described having its carrier composed of a plurality of carrier-belts of lengths approximating that of bricks, the said carrier-belts being power-driven independently of the movement of the clay, whereby the cut bricks may be discharged from said belts by the power applied to the belts, substantially as set forth. 5
2. A machine substantially as described comprising carrier-belts and cross-plates arranged between the said belts and slightly separated at their adjacent edges, forming a groove to receive the cutter, substantially as set forth. 15
3. In a machine substantially as described, the combination of the carrier-belts separated at their ends, the cutting-wires arranged to descend between the adjacent ends of the belts, and mechanism for driving said carriers subsequent to the descent of the cutting-wire, whereby the wires may cut down through the slabs of clay to form the brick lengths and the brick lengths be discharged off such carriers before the wire ascends, substantially as and for the purposes set forth. 25
4. A machine substantially as described having its carrier composed of belt-sections and having clutch devices connecting said belt-sections with their drive devices, whereby the belt-sections may be moved forward by the clay as the latter is forced onto the carrier, substantially as set forth. 30
5. In a machine substantially as described, the combination, with the endless belts constituting the carrier, of cross-plates arranged between the adjacent ends of the said belts and having their upper sides arranged flush with the tops of the belts, substantially as set forth. 35
6. In a machine substantially as described, the combination of the endless belts arranged in series and having their shafts provided with sprocket-wheels and clutch connections, the sprocket-chain meshing with said belts and drive mechanism, substantially as set forth. 45
7. In a machine substantially as described, the cutter comprising the spring-bow adapted at its ends to support the cutting-wire and provided with a compressing device connected with the spring-bow by which to forcibly adjust said ends toward each other to facilitate the application of the wire, substantially as set forth. 50
- 55

8. In a machine substantially as described, the combination, with the spring-bow, of the compressing device comprising a lever fulcrumed between its ends, bearing at one end against the lower end of one of the arms and having a pawl, and a ratchet for engagement by said pawl, substantially as set forth. 60

9. In a machine substantially as described, the combination of the cutter-spring bow, the wire extended between the ends thereof, the cross rod or bolt extending between the arms of said spring-bow, the supplemental spring on said rod or bolt, the compressing-lever, and the pawl and ratchet, substantially as set forth. 65

10. In a machine substantially as described, the combination of the framing, the carrier, the cutting devices arranged to cut vertically, the slide-rod, means for reciprocating such rod, intermediate connections between the rod and the cutting devices, whereby the movement of the rod will operate such devices, a drive-shaft gearing between such shaft and the carrier, including a clutch, and connections between the said clutch and the slide-rod, whereby the movement of the slide-rod will operate to throw the carrier into and out of clutch with the drive-shaft, all substantially as and for the purposes set forth. 70

11. The combination, in a machine substantially as described, of the cutter-frame having leg portions, the main frame having guides for said leg portions, the rock-shaft having cranks, a link or connecting rod joining one of such cranks with the cutter-frame, 85 and the slide-rod connected with the other crank, all substantially as set forth.

12. The combination, substantially as described, of the main frame, the cutter-frame, the carrier, a sprocket-belt by which the rollers of the carrier may be driven, a shaft 13, having a clutch-section 14, gearing connecting said shaft 13 with one of the rollers of the carrier, the drive-shaft 16, and clutch-section 14, the slide-rod and the rock-shaft having cranks for connection with the slide-rod and with the cutter-frame, and also provided with a crank-arm, by which to operate the clutch-section, all substantially as set forth. 95
